(57) **CLAIM**

The ornamental design for a package for flowable food product, as shown and described.

DESCRIPTION

FIG. 1 is a top front perspective view of a package for flowable food product according to our new design.

FIG. 2 is a top plan view thereof.

FIG. 3 is a bottom plan view thereof.

FIG. 4 is a front elevational view thereof, wherein the rear elevational view is a mirror image of FIG. 4.

FIG. 5 is a right side elevational view thereof; and,

FIG. 6 is a left side elevational view thereof.
